PULPIT OR THE LIKE

Bernard J. Tonning, Grand Rapids, Mich., assignor to American Seating Company, Grand Rapids, Mich., a corporation of New Jersey

Filed Mar. 20, 1959, Ser. No. 55,069

Term of patent 14 years

(Cl. D29—23)

The rear of the pulpit is of open, conventional configuration, and the upper surface of the top is plain and unornamented.

I claim:

The ornamental design for a pulpit or the like, substantially as shown and described.
